United States Patent Office

Des. 225,568

Patented Dec. 19, 1972

225,568

TIRE MOLD-PRESS OR THE LIKE

Robert D. McVay, Columbus, Ohio, assignor to United
McGill Corporation, Columbus, Ohio

Filed May 14, 1971, Ser. No. 143,731

Term of patent 14 years

Int. Cl. D15—99

U.S. Cl. D54—13

FIG. 1 is a perspective view of a tire mold-press or the like embodying this invention.

FIG. 2 is a side elevational view of the mold-press of FIG. 1.

FIG. 3 is a fragmentary elevational view on an enlarged scale of the central portion of the mold-press of FIG. 1.

FIG. 4 is a horizontal sectional view taken along line 4-4 of FIG. 3.

I claim:

The ornamental design for a tire mold-press or the like, substantially as shown.
